AGITATOR FOR MASH TANKS

Andreas R. Keller, Lombard, Ill.

Application July 23, 1937, Serial No. 155,339

3 Claims. (Cl. 259—107)

This invention relates to agitating apparatus, and more particularly to such apparatus especially designed to agitate a machine of the type used for brewing beer or similar beverages.

5 One feature of this invention is that it provides improved agitation, resulting in a better extraction of the desired ingredients from the solids used in such brewing; another feature of this invention is that it is adapted to achieve 10 such improved agitation with less power than now used on such agitators; yet another feature of this invention is that the agitating apparatus is so designed that clogging is prevented; other features and advantages of this invention will be 15 apparent from the following specification and the drawing, in which:

Fig. 1 is a partial top plan view of a tank having therein agitating apparatus embodying this invention; Fig. 2 is a vertical sectional view of the 20 same tank; Fig. 3 is an end elevation of the blades and scoops mounted thereon; and Fig. 4 is a vector diagram of certain of the forces developed.

In the process of brewing beer and similar beverages various solids, such as malt, hops, barley 25 and the like are mixed with water to achieve the desired extraction, and thus certain tanks in the process, such as rice tanks, mash tuns, and brew kettles, have therein a mixture comprising both liquid and solids. In order to extract as much 30 as possible of the desired elements from the solids it is necessary that these mixtures be agitated, and such tanks are generally provided with agitating apparatus of various kinds, driven by a prime mover of some type external of the tanks.

35 The present invention provides improved agitating means, which not only so distributes the solids through the liquid as to secure better extraction, but may be operated with less power than conventional types of agitators. The agitator 40 comprises in general a propeller consisting of two inclined blades, each blade having mounted thereon substantially tubular inclined scoops.

In the particular embodiment of the invention 45 illustrated herewith a tank 10, which may be of any desired shape, is here shown as having substantially cylindrical side walls 11 and a straight bottom 12, the bottom being provided with an outlet 13 which may be closed by valve means, not here shown, since it forms no part of the 50 present invention. The tank has angularly disposed therein near the periphery thereof a heating tube or coil 14, adapted to have steam or any other hot fluid passed therethrough in heat transfer relation to the mixture in the tank. The tank, 55 tube, and other metal parts within the tank are

preferably of copper, although they may be of any metal adapted to withstand exposure to the mixtures in the tank.

The tank is here shown as having extending 5 therein through the bottom thereof a rotatable shaft 15, which shaft is journaled in a suitable bearing 16 and connected to some prime mover, not here shown, in order that rotation thereof may be effected. Within the tank the shaft 15 carries a propeller 17, here shown as comprising 10 a hub 18 and blades 19 and 20. These blades are similar, each being mounted on the opposite side of the shaft from the other and being perpendicular thereto so that they lie in a substantially horizontal plane. The blades are relatively thin throughout the major part of their width, and are laterally inclined, as may be particularly seen from Fig. 3. This inclination is about 30°, and the lower end is on the forward part of the blade and lies closely adjacent the 20 bottom of the tank. When the forward part is spoken of, it is meant that part which is the leading edge during rotation of the propeller, and first contacts the mixture in the tank. In the particular embodiment of the device illustrated herewith the agitator is adapted to rotate 25 in a clockwise direction, viewed from above, as may be seen from a consideration of Fig. 1.

Each of the blades has mounted thereon and carried closely thereabove a plurality of tubular 30 scoops. Since the arrangement of these scoops on each blade is identical only those on the blade 20 will be described. Each scoop is of closed tubular form, of any cross-sectional shape, being here shown as of substantially cylindrical form, 35 without any slots or openings therethrough or any projections which might cause solids to pack thereagainst. The scoops preferably decrease in size toward the end of the blade, are set at an angle of 30° with the horizontal, and are 40 of sufficient length that their upper or rear ends extend slightly above the normal upper level of the solids 21 in the tank. Reference to Fig. 2 will show that the tank has therein a liquid 22 as well as the solids, but that the solids normally tend to 45 settle to the bottom as illustrated.

In an 18-foot tank, for example, the scoop 23 would have its center about seventeen inches from the center of the shaft 15, and would have a diameter of about nine inches, and a length along 50 a horizontal projection of about eighteen inches. That is, although the walls of the scoop are inclined at an angle of 30° to the horizontal the two ends are preferably vertical. Succeeding scoops might well be placed about twelve inches 55

apart, with respect to their centers, and would progressively decrease in size. That is, scoop 24 should be about eight inches, scoop 25, seven inches, scoop 26, six inches, and scoop 27, five inches in diameter. It will be noted that the bottom lines of the scoops are all on the same horizontal level, rather than the center.

Rotation of the propeller and scoop causes the solids 21 to be thrown upwardly as a result of contact with the forwardly moving inclined surfaces of the propeller blades and scoops. Material which enters the scoops is thrown up into the liquid 22, having an upward component of force as it leaves the back end of the scoops. This will be readily understood from consideration of the vector diagram in Fig. 4. Assuming the agitator is being rotated such that solids enter any particular scoop with a 90-pound force, the force along the direction which the material travels through and leaves the scoops is about 80 pounds, as illustrated. Thus, as the material leaves the scoop it would have an 80-pound force in the direction 30° upwardly from the horizontal, which might again be resolved into a 40-pound upward vertical component and about a 70-pound horizontal component. The upward force developed would cause the solids to rise considerably in the liquid in the tank, so that the desired extraction might be achieved as they settle back. The upper surfaces of the blades, of course, also throw the solids upwardly with a similar action and a similar diagram of forces, although to a lesser extent.

The particular agitating apparatus illustrated herewith achieves a very thorough mixing of the solids with the liquid, and the desired extraction, with a minimum expenditure of power. All parts contacting the solids in the mixture are so shaped and arranged as to have little dead loss, as much power as possible being converted into an upward or vertical component of motion. The decreasing size of the scoops enables the blades to be rotated at reasonable speed without undue resistance.

While I have shown and described certain embodiments of my invention, it is to be understood that it is capable of many modifications. Changes, therefore, in the construction and ar-

angement may be made without departing from the spirit and scope of the invention as disclosed in the appended claims, in which it is my intention to claim all novelty inherent in my invention as broadly as permissible, in view of the prior art.

I claim:

1. Agitating apparatus of the character described for a tank adapted to hold a mixture comprising fluid and solids, including: a vertical rotatable shaft; a pair of horizontal blades mounted on said shaft and extending in opposite directions therefrom, said blades being laterally inclined and having their lower edges on the forward side and closely adjacent the bottom of said tank; and a plurality of inclined tubular scoops mounted on said blades, said scoops all having their lower ends forward and progressively decreasing in diameter toward the ends of said blades. 20

2. Agitating apparatus of the character described for a tank adapted to hold a mixture comprising a fluid and solids, including: a vertical rotatable shaft; a pair of horizontal blades mounted on said shaft and extending in opposite directions therefrom, said blades being laterally inclined and having their lower edges on the forward side and closely adjacent the bottom of said tank; and at least three inclined tubular scoops mounted on each of said blades and progressively decreasing in diameter toward the ends of said blades, each of said scoops being set at an angle of about thirty degrees to the horizontal and being of sufficient length to extend above the upper level of the solids in said tank. 30

3. Agitating apparatus of the character described for a tank adapted to hold a mixture comprising a fluid and solids, including: a vertical rotatable shaft; horizontal blades mounted on said shaft and extending in opposite directions therefrom, said blades being laterally inclined and having their lower edges on the forward side adjacent the bottom of said tank; and a plurality of inclined scoops mounted on said blades, said scoops all having their lower ends 40 forward and progressively decreasing in size toward the ends of said blades. 45
